DESIGN FOR A SHOE

George Thomas, Los Angeles, Calif., assignor of one-half to Benjamin Warshauer, Stockton, Calif.

Application June 28, 1941, Serial No. 101,780

Term of patent 3½ years

To all whom it may concern:

Be it known that I, George Thomas, a citizen of the United States, residing at Los Angeles, in the county of Los Angeles and State of California, have invented a new, original, and ornamental Design for a Shoe, of which the following is a specification, reference being had to the accompanying drawing, forming a part thereof, and in which

Fig. 1 is a top plan view of a shoe, showing my new design, the essential features of which are illustrated in full lines.

Fig. 2 is a side elevational view of the shoe.

I claim:

The ornamental design for a shoe, as shown and described.

GEORGE THOMAS.
